Fig. 1

Circuit diagram showing a radio receiver stage. The input signal enters through terminal 1. The circuit includes a grid leak detector with diodes 23 and 36, a pentode stage with 4.3 μ A2, and a triode stage with 4.3 μ A3. The output is taken from terminal C. Various bypass capacitors (33, 34, 35, 36, 37, 38, 39, 40, 41, 42, 43, 44, 45) are connected to ground. A grid leak oscillator is also present. Components are numbered 1 through 45.

Fig. 3

Graph showing the relationship between Input in Microvolts and Output in Volts. The x-axis is labeled "INPUT IN MICROVOLTS" and the y-axis is labeled "OUTPUT IN VOLTS". The curve shows a threshold effect, with regions A, B, C, and D labeled. The threshold is marked with a dashed line.

Fig. 4

Graph showing the Demodulator Input and Threshold. The x-axis is labeled "FREQUENCY" and the y-axis is labeled "VOLTS". The graph shows a series of pulses labeled 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100. The threshold is indicated by a dashed line.

AUTOMATIC REGULATION IN RADIO RECEIVERS

Sidney Y. White, Chicago, Ill., assignor to Victor S. Johnson, Chicago, Ill.

Application July 22, 1936, Serial No. 91,945

20 Claims. (Cl. 250—20)

This invention relates to improvements in high-frequency signaling systems, and more particularly to systems employing modulated high-frequency signals for the transmission of intelligence. More specifically, this invention relates to improvements in radio broadcast receivers or other types of radio receivers adapted to respond to a particular desired signal.

An object of this invention is to provide an improved type of noise suppression means for radio receivers.

An additional object of the invention is to provide means for preventing appreciable response from a radio receiver in the absence of an input signal having a predetermined initial minimum amplitude.

Still a further object of the invention is to provide means for maintaining the output signal of a radio receiver substantially constant as the amplitude of an input signal, the initial amplitude of which exceeds a predetermined minimum value, varies over a wide range.

Another object of this invention is to provide a definite and widely adjustable threshold value for the input signal to a radio receiver below which no response is obtained, and above which the response is maintained substantially uniform at a desired level.

Radio receivers which are equipped with means for automatically controlling their amplification inversely in accordance with the strength of the input signal have the disadvantage that the amplification automatically rises to a maximum degree when the receiver is not tuned to a signal of at least moderate strength. This rise in amplification or sensitivity produces a great increase in the response of the receiver to signals too weak to be useful, and to extraneous disturbances, so that the listener may hear harsh and unpleasant sounds as the receiver is tuned from one strong signal to the next. This difficulty is not overcome by retarding the manual volume control of the receiver, since to do so also reduces below audibility the response to the signals from which a selection is to be made.

Various types of "noise gates" and "sensitivity controls" have, in the past, been employed to minimize this inherent disadvantage of receivers having automatic amplification control means. The first-mentioned devices all depended upon the amplitude of the input signal for operation, so that only relatively strong signals were able to get through the gate and produce a response. Likewise, however, extraneous disturbances such as static and other undesirable electrical noises

were able to get through the gate and produce a response, provided they were of sufficient strength. Noise gates had the further disadvantage of producing serious distortion of an input signal having an amplitude close to the threshold value for which the gate was initially adjusted. For these reasons, noise gates are not a satisfactory solution of this problem in a receiver having automatically controlled amplification.

Another attack on this problem was made by employing means for limiting the maximum sensitivity of the receiver. In this way, the performance of the receiver on relatively powerful input signals was not appreciably affected, but its response to relatively weak undesired disturbances was substantially reduced. Although reducing the maximum sensitivity of the receiver was partially successful in preventing signals too weak to be useful and extraneous noises from being objectionable, this method had the distinct disadvantage of greatly decreasing the ability of the receiver to cope with fading of desired signals. As the signal faded, its amplitude would fall below the threshold value for which the sensitivity control had been adjusted, and no useful response would then be obtained. To keep extraneous response at a minimum between the desired signals, the threshold value had to be set relatively high, so that even strong input signals frequently faded below the threshold value. Providing means for regulating the maximum sensitivity of a receiver, therefore, is a satisfactory method of preventing any appreciable response only when the input signal initially exceeds a predetermined minimum value and never fades below that value.

The arrangements of the present invention, however, provide an improved form of noise suppression system which discriminates between input noise and input signals and which is automatically unlocked only by an input signal having a predetermined initial minimum amplitude. Furthermore, the presence of such an input signal automatically lowers the threshold value in such a manner that the signal after being received may vary over a wide range, due to fading or other changes in transmission, without falling below the new threshold value of the receiver. An additional advantage of the arrangements herein disclosed is that the adjustable threshold value is definite and distinct and there is no distortion of a signal having an amplitude only slightly greater than the threshold value.

Although the arrangements of the present invention are adapted for use in conjunction with

any type of radio receiver, they are particularly useful in receivers which are provided with means for automatically regulating their amplification, and are especially suitable for use in receivers also employing automatic resonance adjusting means, such, for example, as disclosed in my co-pending application for Letters Patent, No. 29,244, filed July 1, 1935. When used in conjunction with such a system, the arrangements herein disclosed are capable of providing a radio receiver which responds only to signals of a predetermined initial minimum amplitude, to which the receiver is automatically correctly tuned.

15 It is a further object of the present invention, therefore, to provide a noise suppression system particularly adapted to and having especial advantages when used in conjunction with systems including automatic resonance adjusting means. 20 When used in conjunction with such systems, the arrangements of the present invention permit adjustment of the minimum signal to which the automatic resonance adjusting means will respond, and thus eliminate the unpleasant sounds 25 which might otherwise be produced due to the high amplification existing when the receiver is adjusted to relatively weak signals.

Additionally, and of even greater importance in conjunction with systems incorporating automatic resonance adjusting means, when the various components of the arrangements about to be described are chosen to have the proper values, the automatic resonance adjusting means is caused to relinquish its control with respect to 35 any particular signal when the tuning means has been advanced a predetermined amount beyond the point corresponding to resonance with that signal. It has been found in conjunction with automatic resonance adjusting means that 40 there is no problem in arranging the system in such a way that it will seize upon any new signal into proximity to which the receiver is tuned, but in such systems it remains a severe if not an unsolved problem to so arrange the system that it will relinquish control when the tuning means has been advanced a reasonable amount beyond 45 the signal. When the receiver is tuned from one reasonably strong signal directly into another reasonably strong signal, this problem is not difficult of solution; but when tuning proceeds into a region in which there is no signal or only a very weak one, the automatic resonance adjusting means does not relinquish its control as it should, but continues to maintain the receiver tuned to 55 the signal to which it was previously adjusted.

It will be understood, therefore, that my present invention contemplates several highly advantageous improvements applicable to automatic resonance adjusting systems, but also having utility of a high order in receivers in which no automatic resonance adjusting means are employed.

The above and other objects of my invention will more clearly appear by reference to the accompanying drawings illustrating a preferred embodiment thereof, in which:

Fig. 1 is a schematic diagram of one form of the invention incorporated in a portion of a radio receiver;

70 Fig. 2 is a schematic diagram of a superheterodyne radio receiver incorporating both the arrangements of the present invention and the automatic resonance adjusting means disclosed in my co-pending application for Letters Patent, 75 No. 29,244;

Fig. 3 is a graph showing the input vs. output characteristic of the radio receiver, a portion of the circuit of which is shown in Fig. 1; and

Fig. 4 is a graph showing the characteristic of the radio receiver, the circuit of which is shown in Fig. 2.

Referring to Fig. 1, vacuum tube 1 is arranged to operate as an intermediate-frequency amplifying device, its grid or input circuit including tuned circuit 2 and its plate or output circuit including tuned circuit 3. Cathode 4 of vacuum tube 1 is grounded. By-pass capacitors 5 and 5a offer a low-impedance path for high-frequency currents in the input and screen-grid circuits, respectively, of vacuum tube 1. 15

Tuned circuit 3 is coupled to tuned circuit 6, which is included in the grid or input circuit of vacuum tube 7. The input circuit of vacuum tube 7 also includes filter resistor 8 and volume-control potentiometer 9. Cathode 10 of vacuum tube 7 is grounded. Capacitors 11 provide low-impedance paths for the high-frequency currents in the input circuit of vacuum tube 7. The plate circuit of vacuum tube 7 includes load resistor 12, and the screen-grid 13 of vacuum tube 7 is 25 by-passed to ground by means of capacitor 14. Plate 15 of vacuum tube 7 may be connected to screen-grid 13 by means of switch 16. Screen-grid 23 of vacuum tube 1 is connected to plate 15 of vacuum tube 7. 30

Vacuum tube 17 includes two diode rectifiers and a triode audio-frequency amplifier. The grid 18 of the triode portion is connected through capacitor 19 to the movable arm of volume-control potentiometer 9. The plate circuit of the 35 triode portion of vacuum tube 17 includes load resistor 20 and filter resistor 21. Cathode 22 of vacuum tube 17 is grounded.

Resistors 24, 25 and 26 are connected in series between a source of negative voltage E and plate 40 15 of vacuum tube 7. Grid leak 27 is connected between the junction of resistors 24 and 25 and grid 18 of vacuum tube 17. Capacitor 28 bypasses the junction of resistors 24 and 25 to ground. The junction of resistors 25 and 26 is 45 connected to diode anode 29 of vacuum tube 17. Resistors 30 and 31 are connected in series between source of negative voltage E and ground. Resistor 30 is shunted by potentiometer 32 and resistor 33 in series. 50

Control-grid 34 of automatic amplification control amplifying vacuum tube 35 is connected to control-grid 36 of vacuum tube 1. Cathode 37 of vacuum tube 35 is grounded. The plate circuit of vacuum tube 35 includes the primary winding of transformer 38. One terminal of the secondary winding of transformer 38 is connected to diode anode 39 of vacuum tube 17. The other terminal is connected through resistors 40 and 41 in series to the movable arm of potentiometer 32. The low-potential terminal of tuned circuit 2 is connected through resistor 42 to the junction of resistors 40 and 41. The junction of the secondary winding of transformer 38 and resistor 40 is bypassed to ground by capacitor 43. A filter consisting of series resistor 44 and shunt capacitor 45 is connected to the high-potential terminal of capacitor 43. 55

In operation, let it first be assumed that no signal voltage is present across tuned circuit 2. 70 The control-grid 46 of vacuum tube 1 has substantially the same potential as does cathode 10 of vacuum tube 7, and therefore this tube draws a relatively high plate current. The high plate current of vacuum tube 7 flowing through re- 75

sistor 12 produces a large voltage drop, so that plate 15 of vacuum tube 7 may have a positive potential of only about 25 volts. Since screen-grid 23 of vacuum tube 7 is connected to plate 15 of vacuum tube 7, the amplification of intermediate-frequency amplifying vacuum tube 1 is materially reduced due to the very low screen-grid voltage. The actual amplification of vacuum tube 1 is determined by the adjustment of potentiometer 32, which alters the direct-current potential applied to control-grid 36 of vacuum tube 1.

The values of resistors 24, 25 and 26 are so chosen that, in the no-signal condition, a negative bias potential sufficient to block the tube is applied to grid 18 of the triode portion of vacuum tube 11. With this bias voltage, the plate current of the triode portion of vacuum tube 11 is substantially zero and the tube is therefore incapable of amplification.

Now let it be assumed that a relatively strong signal voltage appears across tuned circuit 2. Even though the amplification of intermediate-frequency amplifying vacuum tube 1 is low, sufficient signal voltage appears across tuned circuit 6 to develop a potential drop across resistor 8 and potentiometer 9 in series because otherwise unbiased control-grid 46 of vacuum tube 7, with cathode 10, acts as a diode rectifier. This voltage drop causes control-grid 46 of vacuum tube 7 to become negative with respect to cathode 10, producing a substantial decrease in the plate current of vacuum tube 7. This in turn reduces the potential drop across resistor 12 and increases the voltage applied to screen-grid 23 of intermediate-frequency amplifying vacuum tube 1, with a resultant increase in the amplification of vacuum tube 1.

This further increases the signal across tuned circuit 6, which again decreases the plate current of vacuum tube 1, resulting in a cumulative unstable condition which continues until full amplification has been restored to vacuum tube 1, and the threshold has in effect disappeared. The rate at which the amplification is restored depends upon the value of capacitor 5a.

To re-establish this threshold, it is necessary that the input signal voltage decrease, either by detuning or due to severe fading, to a value where the signal, despite full gain in vacuum tube 1, is too weak to maintain a substantial negative bias on control-grid 46 of vacuum tube 7. Under these conditions, the plate current of vacuum tube 7 increases, with consequent greater voltage drop in resistor 12, thus decreasing the voltage on the screen-grid of vacuum tube 1, further decreasing the signal, and another cumulative unbalance occurs, ending in the original threshold being re-established.

The increase in the potential of plate 15 of vacuum tube 1 causes diode anode 29 to become positive with respect to cathode 22 of vacuum tube 11. Since the internal resistance of the diode rectifier is now small compared with the values of resistors 24, 25 and 26, the junction of resistors 25 and 26 is effectually grounded. The values of resistors 24 and 25 are so chosen that the proper negative bias voltage is applied to grid 18 of the triode portion of vacuum tube 11 for normal operation as an audio-frequency amplifier. The rate at which vacuum tube 11 is restored to normal operation is determined by the value of capacitor 28.

The audio-frequency component of the signal appears across volume-control potentiometer 9,

and is tapped off and supplied to grid 18 of vacuum tube 11 by means of capacitor 19. Control-grid 46 of vacuum tube 7 operates simultaneously as the anode of a diode and as the control-grid of a tetrode, the tetrode functioning to amplify the direct-current potential variations which appear across resistor 8 and potentiometer 9 in series.

By making the time required for unblocking the audio-frequency amplifying vacuum tube 11 considerably greater than that required to restore the amplification of intermediate-frequency amplifying vacuum tube 1, the system is made unresponsive to bursts of static and other electrical disturbances of short duration regardless of their amplitude. A continuous signal of predetermined initial minimum amplitude, however, first restores the amplification of intermediate-frequency amplifying vacuum tube 1 and then unblocks the audio-frequency amplifying portion of vacuum tube 11. This definite order of operation has the additional and important advantage of preventing response in the form of an output signal across resistor 20 until the strength of the input signal is well above the threshold value, thus preventing any distortion which might occur at or near the threshold value from being present in the output of the system.

This threshold distortion is of two kinds. If the signal is gradually increased from zero, it will first appear across tuned circuit 6 at very low intensity and the diode rectification action of control-grid 46 of vacuum tube 7 will only rectify the peaks of the modulation, without generating an appreciable negative bias sufficient to change its plate current. Since vacuum tube 11 is blocked until a definite amount of change of plate current of vacuum tube 7 occurs, the receiver produces no sound while the signal is breaking down this threshold.

The other kind of threshold distortion occurs during the period in which the grid bias of vacuum tube 11 is decreasing from the blocked to the operating condition. However, due to the cumulative snap interaction of vacuum tubes 1 and 11, the grid-bias voltage on vacuum tube 11 is changed so rapidly that this distortion is passed through in a small fraction of a second, and consequently is not noticeable.

Since the amplification of intermediate-frequency amplifying vacuum tube 1 is substantially increased by the presence of an input signal having an amplitude above a predetermined initial minimum value, the threshold value is lowered as a result. Thus there is a reserve of amplification to aid in counteracting fading or other changes in the strength of the input signal. This automatic lowering of the threshold value is an important feature of the present invention.

The voltage across tuned circuit 2 is also applied to control-grid 34 of automatic amplification control amplifying vacuum tube 35. After being amplified by vacuum tube 35, the signal voltage is applied to diode anode 39 of vacuum tube 11 by means of coupling transformer 38. Diode anode 39 is initially negative with respect to ground by an amount dependent upon the setting of potentiometer 32. When the signal voltage is sufficiently high to overcome this initial negative bias, a direct-current voltage is developed across diode load resistors 40 and 41 in series. This voltage is utilized to provide automatic amplification control of the vacuum tubes preceding vacuum tube 1 in the receiver, series resistor 44 and shunt capacitor 45 preventing

fluctuations due to modulation of the signal voltage from reaching the controlled vacuum tubes, the control-grids of which may be operatively connected to the junction of resistor 44 and capacitor 45 at AVC.

The control voltage which is developed across resistor 41 is applied to the control-grid of intermediate-frequency amplifying vacuum tube 1, the fluctuations due to modulation being removed by series resistor 42 and shunt capacitors 5 and 43a. Thus vacuum tube 1 is regulated to a lesser extent than are the preceding vacuum tubes by the automatic amplification control means, but at the same time contributes toward the over-all effectiveness of this control means. In no event, however, is the amplification of this vacuum tube reduced by the automatic amplification control means to an extent sufficient to deprive vacuum tube 7 of the signal voltage necessary to maintain its plate current at a low value. The fact that the present invention discloses an automatic noise suppression system which does not interfere with or appreciably limit the range of operation of the automatic amplification control means is another of its important features.

The setting of potentiometer 32 determines the initial negative bias voltage which is applied to the control-grids of the preceding vacuum tubes as well as that applied to control-grid 36 of intermediate-frequency amplifying vacuum tube 1. This potentiometer functions, therefore, both as means for adjusting the maximum sensitivity of the receiver and as an adjustment of the initial threshold value of input signal to which the receiver is responsive. For example, moving the arm of potentiometer 32 toward the terminal which is connected to resistor 33 decreases the maximum sensitivity of the receiver and simultaneously raises the threshold value, adapting the receiver to receive strong signals with a minimum of extraneous noise between signals. Moving the arm of potentiometer 32 toward the junction of resistors 30 and 31, however, increases the maximum sensitivity of the receiver and at the same time decreases the threshold value, thus adapting the receiver for the reception of relatively weak signals. An important feature of the present invention is that only a single control is required to adjust the system for any particular condition of operation, thus greatly simplifying the construction and operation of the complete receiver. The entire noise suppression system is rendered inoperative merely by throwing switch 18 to the lower position, and this switch may readily be arranged so that it is operated by a slight movement of the arm of potentiometer 32 at the high-sensitivity end. The switch connects plate 15 of vacuum tube 7 and screen-grid 23 of vacuum tube 1 to the screen-supply point B, restoring full amplification to vacuum tube 1 and ensuring correct bias for vacuum tube 17.

It will be understood that the noise suppression system just described differs in fundamental particulars from the various "noise gates" and "sensitivity controls" of the prior art, in that it comprises a sequential series of automatic operations, this series being inherently non-reversible. It will also be understood that this noise suppression system, in and of itself, has highly advantageous application not only in radio receivers but equally as well in any device or apparatus in which it is desired to establish operative conditions in response to initial conditions,

without regard to subsequent fluctuations. Also, in radio receivers, it is possible by suitable choice of constants to cause the noise suppression system to operate in response to relatively small changes in signal level at the demodulator, such as might result if the receiver is tuned only slightly away from resonance with a desired signal. Such an arrangement prevents any response from the loud speaker under conditions which might otherwise produce serious distortion, and operates to give a result similar to that secured by automatic resonance adjustment.

Fig. 2 is the schematic diagram of a multi-band superheterodyne radio receiver which incorporates not only the improved noise suppression system which is shown in Fig. 1, but also the automatic resonance adjusting means which is disclosed in my copending application for Letters Patent, No. 29,244. This receiver employs thirteen vacuum tubes arranged as follows: a radio-frequency amplifying vacuum tube 46; a modulator vacuum tube 47; a local oscillator vacuum tube 48; a first intermediate-frequency amplifying vacuum tube 1; a combined demodulator, second intermediate-frequency amplifying and direct-current amplifying vacuum tube 7; a combined first audio-frequency amplifying automatic amplification control rectifying and bias voltage determining vacuum tube 17; a second audio-frequency amplifying vacuum tube 30 49; a push-pull audio-frequency output stage consisting of vacuum tubes 50 and 51; a power rectifier vacuum tube 52; an automatic amplification control amplifying vacuum tube 35; a director vacuum tube 53; and a corrector vacuum tube 54. With the exception of the novel features herein disclosed and those disclosed in my co-pending application for Letters Patent, No. 29,244, the receiver is of conventional design and operates in the usual manner.

As between Figs. 1 and 2, corresponding parts are designated by the same numeral. It is unnecessary, therefore, to repeat a detailed description of the novel noise suppression system herein disclosed as to its operation in the receiver of Fig. 2, except insofar as the results obtained differ from those stated in the discussion of Fig. 1. In addition to functioning as a rectifier and as a direct-current amplifier, vacuum tube 7 serves as an intermediate-frequency amplifier. The plate circuit of vacuum tube 1 includes series inductor 55a and coils 55 which are coupled with coils 56a and 56b associated with vacuum tube 53 to form the director portion of the automatic frequency adjusting system. The director is arranged to supply a direct-current voltage to control-grid 57 of vacuum tube 54, which is arranged to function as the corrector portion of the automatic frequency adjusting means. The input capacitance of vacuum tube 54, in series with capacitor 58, is in shunt with the plate load of oscillator vacuum tube 48.

In the presence of no input signal or of a signal having a value lower than the predetermined threshold value for which the receiver may be adjusted by means of potentiometer 32, the amplification of intermediate-frequency amplifying vacuum tube 1 is very low and the signal voltage appearing across tuned circuit 6 is therefore negligible. Therefore negligible voltage reaches director vacuum tube 53, and the control-grid bias voltage of vacuum tube 54 is determined solely by the potential at tap A on the power-supply divider network. The value of the voltage at tap A is so chosen that the input capacitance

of vacuum tube 54 is approximately at its mid-point.

When the initial amplitude of the input signal exceeds the threshold value, the amplification of vacuum tube 1 is greatly increased by the action of the automatic noise suppression system, with the result that a strong signal current flows through coils 55 in the plate circuit of vacuum tube 7. Since coils 56a and 56b are tuned respectively to a frequency slightly lower than the intermediate frequency of the receiver and to a frequency slightly higher than the intermediate frequency, the polarity of the direct-current voltage which is supplied by the director to the corrector depends upon whether the frequency of the signal current in coils 55 is higher or lower than the nominal intermediate frequency of the receiver. If the signal frequency is exactly correct, no voltage is supplied to the corrector by the director. The degree and the sense in which the oscillator frequency is corrected by the corrector depend respectively upon the amplitude and the polarity of the voltage supplied by the director.

The high-frequency amplification of the receiver is regulated automatically by a system which includes amplifying vacuum tube 35 and diode anode 38 of vacuum tube 17. A direct-current control voltage is developed across diode load resistors 40 and 41 in series, when the signal voltage across the secondary winding of transformer 38 exceeds a minimum value determined by the setting of potentiometer 32. The full control voltage is applied to the control- grids of vacuum tubes 46 and 47, and a portion of the control voltage is applied to the control-grid of vacuum tube 1. The performance of the delayed, amplified automatic amplification control is such that the signal voltage across tuned circuit 6 remains substantially constant as the input signal voltage varies over a wide range.

When switch 16 is thrown to the lower position, not only is the automatic noise suppression system rendered inoperative as explained above in connection with Fig. 1, but also the automatic frequency adjusting means is no longer in operation, since a negative voltage is applied to screen-grid 13 of vacuum tube 7, rendering it incapable of amplification and thus preventing any signal voltage from reaching vacuum tube 53. With switch 16 in the lower position, the receiver functions just as does any standard superheterodyne, but with the switch in the upper position, the normal operation of the receiver is supplemented by the automatic frequency control system and by the automatic noise suppression system which are associated with it.

As has already been pointed out, a major difficulty in the design of automatic resonance adjusting systems lies in so arranging the system that it will relinquish a station once it has been tuned in. The intermediate-frequency amplifier inherently tends to stay locked on the station as the tuning dial of the receiver is turned, until the limit of oscillator frequency control has been reached, when the oscillator frequency is again controlled by the dial movement. If this dial movement be further continued, the oscillator is forced so far out of correct relation with the signal that the selective frequency cut-off of the intermediate-frequency amplifier is approached, and a decrease in the voltage supplied to the director results. This decreased voltage tends to release the oscillator and establishes an unstable condition resulting in dropping the signal and

re-aligning the oscillator with the dial setting. During this process, however, the signal has departed widely from true resonance with the intermediate-frequency amplifier, and serious distortion has resulted.

The conditions which must be fulfilled if this difficulty is to be avoided, and which are achieved by the present invention, are as follows:

1. The amount of control on the oscillator must be limited and must be uniform throughout the band. This is necessary in order that a reasonable amount of movement of the dial will exhaust the control possibilities of the system, and restore control to the dial.

2. The director voltage must be limited, and must be relatively independent of signal strength. This is accomplished in a two-fold manner, first by the automatic amplification control and second by operating the tube driving the director as a limiter tube.

3. The voltage delivered by the director ordinarily contains transients of considerable magnitude and the amplitude of these transients increases as the oscillator departs increasingly from correct relation with the signal. These transients must not be suppressed, but are utilized as well now be made clear.

In Fig. 2 vacuum tube 7 excites circuits 56a and 56b through coils 55. These feed their respective diodes and generate opposing direct-current voltages across the resistors shown. This differential voltage is applied to grid 51 of vacuum tube 54 and produces automatic resonance adjustment in the well known manner.

Across each diode load resistor there will also appear audio-frequency voltages and syllabic modulation transients. When the intermediate-frequency amplifier is in accurate relation with the signal, these audio-frequency and transient voltages are in phase opposition and are substantially equal to each other and therefore cancel quite completely. However, as soon as the oscillator departs from correct relation with the signal, the audio-frequency and transient voltages produced by one diode will be substantially greater than those produced by the other and complete cancellation will no longer occur. There will therefore be superimposed on the steady director voltage a series of transients of substantial amplitude. These transients I do not filter out. When control tube 54 is at the limit of control due to the steady direct voltage applied to its grid 57, any substantial relaxing of the control voltage will allow the oscillator to snap back into alignment with the dial setting, which may be for instance 15 kilocycles to one side of the setting exactly corresponding to the frequency of the signal. The transients of random amplitude increase as the oscillator is mistuned, and finally reach an amplitude sufficient to partly cancel the steady direct-current component of the director output voltage. If desired, these transients may be separately amplified and re-introduced to increase their beneficial effects. Corrector tube 54 thus loses control, the oscillator frequency changes to correspond with the dial setting, and the signal has thus been relinquished.

The effect of the audio-frequency transients in causing the corrector to relinquish control of the oscillator when the receiver is detuned, is made more pronounced by resistor 59a, shunted by capacitor 59, and resistor 59b connected in series from the director unit to ground. It will be noted that resistors 59a and 59b form a potential-dividing system, the corrector being connected

to their junction. The values of these two resistors are preferably so chosen that about one-fourth of the direct-current voltage delivered by the director is applied to the corrector. As the receiver is mistuned, the direct-current voltage across resistors 59a and 59b rises, and then, say when the tuning means is about 12 kilocycles from resonance, begins to fall. During the process of tuning away from the signal, the audio-frequency transients have been gradually increasing. By virtue of capacitor 59, which is preferably of a fairly large value, the audio-frequency transients are by-passed across resistor 59a and generate varying voltages only across resistor 59b.

15 The effect of the combination of resistors 59a and 59b and capacitor 59 connected as shown in Fig. 2, therefore, is to increase the effectiveness of the transients in varying the voltage applied to grid 57 of corrector vacuum tube 54 in such a manner that as soon as the direct-current voltage delivered by the director begins to fall, a condition of cumulative instability occurs, and corrector vacuum tube 54 relinquishes control of the frequency of oscillator vacuum tube 17.

20 Additionally, the arrangement of resistors 59a and 59b and capacitor 59 is such that when the voltage delivered by the director fails, capacitor 30 59 discharges not only through resistor 59a which is of a very large value, but also through resistor 59b, which is of much smaller value, and the current through resistor 59b is in a direction opposite to that which flows when the director is delivering appreciable voltage. In the 35 interval during which capacitor 59 is discharging, therefore, there is an actual reversal of potential at the junction of resistors 59a and 59b with respect to ground. This reversed voltage is applied to grid 57 of corrector vacuum tube 54 and produces a change in the frequency of the oscillator such as to immediately cause it to bring into approximate resonance with the intermediate-frequency amplifier the signal in the adjacent channel, if such signal is present.

40 An analysis of the behavior of resistors 59a and 59b and capacitor 59 indicates that the same effect which produces actual reversal of potential on grid 57 of vacuum tube 54 when the voltage from the director fails or falls to zero, operates to enhance the condition of instability in the region between one signal and another in such a way as to cause an instantaneous release of one signal and capture of the next and to narrow the region in which this exchange occurs so that the operation of the automatic frequency 55 adjusting means becomes entirely definite and all tendency to continue to maintain resonance with the undesired signal disappears.

50 By suitable choice of values for resistors 59a and 59b and capacitor 59 it is possible to so emphasize the effects above described that release occurs just as close to the position of exact resonance as does the initial operation of the 60 automatic frequency adjusting means as the receiver is tuned into the signal. I have found, however, that it is preferable to so choose these values that release does not occur quite so close to the position of resonance as does the initial 65 capture of the signal.

70 If the receiver is tuned into the signal from above and also from below the frequency of resonance, and the frequencies at which capture occurs are noted, a "capture band width" may be 75 determined. Similarly, if the receiver is tuned

away from the signal, first by increasing the resonant frequency of the receiver and then by decreasing it, and the frequencies at which release occurs are noted, a "release band width" 5 may be determined. I have found that the best 10 performance is obtained when the "capture band width" is about 85% of the "release band width". It will be understood, however, that by suitable choice of constants, at the discretion of the designer, various relations of these two band widths 10 can be achieved, including the condition in which they are substantially equal.

15 In the tabulation of constants which I give below, as an illustrative embodiment of my invention, the values of resistors 59a and 59b and capacitor 59 are such as to give approximately the 85% relation of the capture and release band widths described above as preferable.

20 It will be understood that when in the specification and claims I refer to capture of a signal, I use this phrase to identify the operation by which the automatic frequency adjusting means acts to change the oscillator to a frequency approximately correct to produce the desired intermediate frequency for that particular signal. 25 Similarly, I refer to release of a signal when I wish to describe the operation by which the automatic frequency adjusting means ceases to maintain the frequency of the oscillator at approximately the correct value to produce the desired 30 intermediate frequency for that particular signal.

35 It will be understood that by suitable choice of constants, the noise suppression system first described may be made to operate at positions closer to the position of exact resonance than the release system just described. With the constants given below, the release system will operate closer to the position of resonance than will the noise suppression system, its mode of operation being through the automatic resonance adjusting system. With other constants, however, the noise suppression system will operate closer to the point of resonance, its mode of operation being to decrease the sensitivity of the receiver and at the same time render the audio-frequency 45 output system inoperative. When the noise suppression system operates in the manner just described, the automatic resonance adjusting system immediately relinquishes its control of the frequency of the oscillator, due to failure of the 50 signal voltage at the demodulator grid.

45 The value of capacitor 28 is of considerable importance. If this capacitor is given a relatively small value, the grid bias voltage on vacuum tube 17 will change almost as rapidly as the 55 voltage on screen-grid 23 of intermediate-frequency amplifying vacuum tube 1. Under these conditions, a severe burst of static may have sufficient duration to cause vacuum tube 17 to become operative, and a sound will be heard. If 60 capacitor 28 is made very large, on the other hand, the grid bias voltage on vacuum tube 17 will change so gradually that when a desired signal is first heard it will be relatively faint, and it will increase in loudness over an appreciable interval before it reaches its final level. Under these circumstances, rapid operation of the tuning means may cause the receiver to pass completely through a signal of sufficient initial intensity to otherwise be heard, without producing an audible sound from the loud speaker. Thus rapid operation of the tuning means will produce a condition of "silent tuning" in which unwanted signals may be passed over without being heard, but as soon as the vicinity of a 70 75

desired station is reached, a slower operation of the tuning means will ensure hearing it.

In the embodiment shown in Fig. 2, the following components or values of constants may be successfully employed, but it will be understood that this is not to be taken as in any way limiting my invention, since other types and values of components may be employed in a circuit arrangement identical with that shown in Fig. 2, 10 or in modifications thereof.

Reference numeral	Type or value
Vacuum tube 1, 7, 35, 46	6K7.
Vacuum tube 17	607.

Terminal E	-20 volts.
Terminal G	-38 volts.

Fig. 3 shows graphically the performance of a radio receiver, a portion of the circuit of which is shown in Fig. 1. Curve A represents the relation between input and output voltages which is obtained when the automatic noise suppression system of the invention is rendered inoperative by the closing of switch 16 in Fig. 1. In this case, 40 the output voltage begins to increase gradually as the input voltage increases and tends to level off at the high-input end as the automatic amplification control system becomes increasingly effective. Small input voltages produce an appreciable response. Curve B shows the performance of the system when the automatic noise suppression system is in operation, that is, with switch 16 of Fig. 1 open. In this case, no output voltage is obtained until the initial input voltage reaches 45 a predetermined threshold value, but when the input voltage increases even slightly above this value the output voltage rises to a point which remains substantially fixed. Thus only signals having a predetermined initial minimum amplitude produce a response from the receiver. The first part of curve B is vertical, indicating that the operation of the automatic noise suppression means of the invention is definite and positive.

Changing the threshold value by adjusting potentiometer 32 of Fig. 1 changes the initial minimum input voltage which will produce a response. Curve C indicates the effect of lowering the threshold value, and curve D indicates the performance obtained when the threshold value 50 is raised. By properly adjusting potentiometer 32 of Fig. 1, the threshold value may be made just high enough to permit response to signals of desired initial amplitude without allowing weaker signals and extraneous disturbances to produce a 55 response.

Referring to Fig. 4, triangles 60-65 represent initial input signals of various amplitudes. It will be understood that the input signals are thus only symbolically represented in this figure. The signal voltage at the input to the demodulator is 5 represented by rectangles 66, 67 and 68, corresponding with input signals 60, 63 and 65, respectively. Input signals 61, 62 and 64, being below the threshold value for which the receiver is adjusted, do not produce any response, due to 10 the action of the noise suppression system. Although input signals 60, 63 and 65 vary considerably in amplitude, the amplitude of the corresponding output signals 69, 67 and 68, respectively, is substantially constant, due to the action 15 of the automatic amplification control system. Furthermore, due to the action of the automatic frequency adjusting means, the response to each signal which has an initial minimum amplitude exceeding the predetermined threshold value is 20 maintained substantially constant in spite of inaccuracies in tuning the receiver within the width of a single channel.

From Fig. 4, it is clear that a receiver which is 25 equipped with the automatic noise suppression system of the present invention and with the automatic frequency adjusting means disclosed in my co-pending application for United States Letters Patent, No. 29,244, produces a response only to input signals exceeding a predetermined 30 initial minimum amplitude and only when the receiver is in proper adjustment for the optimum performance. As such a receiver is tuned slowly over the broadcast band of frequencies, it responds to one relatively strong signal after another with substantial silence between these signals. Moreover, no signal is heard unless the receiver is automatically in correct adjustment 35 for the reception of that signal.

It will be understood that Figs. 3 and 4 are not 40 intended to show graphically the automatic decrease of the threshold value upon the reception of an input signal having a predetermined initial minimum amplitude, which is one of the important features of the present invention and is 45 so described hereinabove.

The application of the present invention is not 50 limited to any particular type of radio receiver. Its advantages may be realized in receivers in which the high-frequency amplification takes 55 place at the frequency of the incoming signal as well as in receivers of the superheterodyne type, in which the greater part of the amplification before final demodulation is accomplished at a relatively low constant intermediate frequency. The arrangements of the present invention are 60 not limited to use in radio receivers. They may be applied with equal success to other systems which are to operate in such a way as to be initially unresponsive to input voltages below a predetermined minimum value. Additional advantageous applications of arrangements within the scope of the present invention will suggest themselves to the man skilled in the art.

Having thus described my invention, what I 65 claim is:

1. A radio receiver including a high-frequency amplifier employing a vacuum tube having a screen-grid, an audio-frequency amplifier employing a vacuum tube having a control-grid, a 70 loud speaker, and means for preventing response from said loud speaker until a signal voltage having an initial amplitude exceeding a predetermined value is impressed upon said means, said means including a rectifier connected to rectify 75

said signal voltage, a resistor across which there is developed a positive voltage of such value as to maintain said high-frequency amplifier at low amplifying efficiency, a connection by which said positive voltage is applied to said screen-grid, a resistor across which there is developed a negative voltage sufficient to maintain said audio-frequency amplifier completely inoperative, a connection for applying said negative voltage to said control-grid, and a time-delaying network for sequentially changing said positive and negative voltages, first on said screen-grid and then on said control-grid, as soon as said signal voltage exceeds said predetermined value, to values which increase the amplifying efficiency of said high-frequency amplifier and render said audio-frequency amplifier operative.

2. A radio receiver including high-frequency and audio-frequency amplifiers; a loud speaker; and automatic regulating means for reducing the amplification of said amplifiers to prevent response from said loud speaker whenever the amplitude of the signal impressed across said means is less than a certain value, for maintaining said amplifiers in said condition of reduced amplification until said amplitude exceeds a substantially higher value, for sequentially restoring the amplification of said high-frequency amplifier and said audio-frequency amplifier as soon as said amplitude exceeds said higher value, and for maintaining said amplifiers in said condition of restored amplification until said signal falls below said first-mentioned value; said automatic regulating means including a rectifier, a network associated with said rectifier and connected to sources of positive and negative potential, time-delaying elements, and connections from said network and said time-delaying elements to said amplifiers.

3. A radio receiver including a high-frequency amplifying vacuum tube having a screen-grid; an audio-frequency amplifying vacuum tube having a control-grid; a loud speaker; and automatic regulating means for preventing response from said loud speaker whenever the amplitude of the signal impressed across said means is less than a certain value and until said signal exceeds a substantially higher value, and for permitting response from said loud speaker as soon as said signal exceeds said higher value; said automatic regulating means including a rectifier, a network associated with said rectifier and connected to sources of positive and negative potential, connections from said network to said screen-grid and said control-grid, and time-delaying elements in said connections.

4. A radio receiver including a high-frequency amplifying vacuum tube having a control-grid, a screen-grid, and an output circuit; a second vacuum tube arranged to function both as a rectifier to produce a direct-current voltage and as an amplifier of said direct-current voltage, said rectifier being coupled to the output circuit of said high-frequency amplifying vacuum tube and said amplifier having an output circuit including a resistor; a third vacuum tube arranged to function as an audio-frequency amplifier and having a control electrode; a direct-current connection from said screen-grid to the low-potential terminal of said resistor; a network consisting of a second and a third resistor in series connected between said low-potential terminal and a source of negative potential; and a time-delaying connection between the junction of said sec-

ond and third resistors and said control electrode.

5. A radio receiver including in combination, tuning means, automatic resonance adjusting means for bringing said receiver into substantially exact resonance with a high-frequency signal selected by approximate setting of said tuning means, and means for causing said automatic resonance adjusting means to release said signal when said tuning means reaches a point displaced a predetermined amount from the setting which would correspond to exact resonance with said signal; said resonance adjusting means including a director unit and a corrector unit, said release-producing means including two resistors in series between said director unit and ground, said ungrounded resistor being shunted by a capacitor, the junction of said two resistors being connected to said corrector unit.

6. A radio receiver including in combination, tuning means, automatic resonance adjusting means for bringing said receiver into substantially exact resonance with a high-frequency signal selected by approximate setting of said tuning means, means for preventing response from said receiver until said signal has an initial amplitude exceeding a predetermined minimum value, and means independent of said response-preventing means for releasing said signal when said tuning means reaches a point displaced a predetermined amount from the setting which would correspond to exact resonance therewith, including a potential-dividing and polarity-reversing network which renders said resonance producing means increasingly unstable as said tuning means is moved away from said setting of exact resonance.

7. The method of preventing undesired sound reproduction in a radio receiving system providing high-frequency and audio-frequency amplifications and tunable to selectively receive any one of a number of different carriers throughout a wide range of frequencies, which comprises restraining said amplifications when the amplitude of the selected carrier is less than a predetermined minimum value and until said amplitude exceeds a value substantially higher than said minimum value, and removing said restraint of said high-frequency amplification and of said audio-frequency amplification in the order named as soon as said amplitude exceeds said higher value.

8. The method of preventing undesired sound reproduction in a radio receiving system employing a vacuum tube having a screen-grid for high-frequency amplification and a vacuum tube having a control-grid for audio-frequency amplification, and tunable to selectively receive any one of a number of different carriers throughout a wide range of frequencies, which comprises applying amplification-restraining potentials on said screen-grid and on said control-grid when the amplitude of the selected carrier is less than a predetermined minimum value and until said amplitude exceeds a value substantially higher than said minimum value, and removing said amplification-restraining potentials from said screen-grid and from said control-grid in the order named as soon as said amplitude exceeds said higher value.

9. A radio receiver including in combination, tuning means for tuning said receiver over a range of frequencies, resonance adjusting means for automatically bringing said receiver into substantially exact resonance with a first high-

frequency signal selected by approximate setting of said tuning means but for releasing said signal when said tuning means is adjusted to select a second signal, and means connected to and actuated by said resonance adjusting means for causing immediate release of said first signal.

10. A radio receiver including in combination, tuning means for tuning said receiver over a range of frequencies, resonance adjusting means for automatically bringing said receiver into substantially exact resonance with a first high-frequency signal selected by approximate setting of said tuning means but for releasing said signal when said tuning means is adjusted to select a second signal, and means for accelerating the release of said first signal by said resonance adjusting means, said release-accelerating means including a potential-dividing and polarity-reversing network so arranged as to render said resonance adjusting means increasingly unstable as said tuning means is moved away from the setting which corresponds to exact resonance with said first signal.

15. 11. A radio receiver including in combination, tuning means for tuning said receiver over a range of frequencies, means for automatically bringing said receiver into substantially exact resonance with a first high-frequency signal selected by approximate setting of said tuning means, means for preventing response from said receiver unless said first signal has an initial amplitude exceeding a predetermined minimum value, means for causing said resonance adjusting means to release said first signal when said tuning means is adjusted to select a second signal, and means independent of said response-preventing means for accelerating the release of said first signal by said resonance adjusting means.

12. A radio receiver including in combination, tuning means for tuning said receiver over a range of frequencies, resonance adjusting means for automatically bringing said receiver into substantially exact resonance with a high-frequency signal selected by setting said tuning means between limits above and below the setting which corresponds to exact resonance with said signal, and means connected to and actuated by said resonance adjusting means for causing immediate release of said signal as said tuning means is adjusted from a point within said limits to a point outside said limits.

13. A radio receiver including in combination, tuning means for tuning said receiver over a range of frequencies, resonance adjusting means for automatically bringing said receiver into substantially exact resonance with a first modulated high-frequency signal selected by approximate setting of said tuning means, means for preventing response from said receiver unless said first signal has an initial amplitude exceeding a certain minimum value, said resonance adjusting means being such that modulation peaks in said first signal cause release of said first signal when said tuning means is adjusted to select a second signal, and means independent of said response-preventing means for accelerating the release of said first signal by said resonance adjusting means.

14. A radio receiver including in combination, tuning means for tuning said receiver over a range of frequencies, resonance adjusting means for automatically bringing said receiver into substantially exact resonance with a high-fre-

quency signal selected by setting said tuning means between limits above and below the setting which corresponds to exact resonance with said signal, means for preventing response from said receiver unless said signal has an initial amplitude exceeding a certain minimum value, and means independent of said response-preventing means for accelerating the release of said signal by said resonance adjusting means when said tuning means is adjusted from a point within said limits to a point outside said limits, said limits being so chosen that said resonance adjusting means releases said signal before distortion of said signal due to inaccurate setting of said tuning means becomes appreciable.

15. A radio receiver including in combination, tuning means for tuning said receiver over a range of frequencies, resonance adjusting means for automatically bringing said receiver into substantially exact resonance with a first high-frequency signal selected by approximate setting of said tuning means but for releasing said first signal when said tuning means is adjusted to select a second signal, means for automatically regulating the high-frequency amplification of said receiver inversely in accordance with the strength of said first signal, and means connected to and actuated by said resonance adjusting means for causing immediate release of said first signal.

16. A radio receiver including in combination, tuning means for tuning said receiver over a range of frequencies, resonance adjusting means for automatically bringing said receiver into substantially exact resonance with a first high-frequency signal selected by approximate setting of said tuning means but for releasing said first signal when said tuning means is adjusted to select a second signal, means for automatically regulating the high-frequency amplification of said receiver inversely in accordance with the strength of said first signal, means for preventing response from said receiver unless said first signal has an initial amplitude exceeding a certain minimum value, and means independent of said response-preventing means for accelerating the release of said first signal by said resonance adjusting means.

17. A radio receiver including in combination, tuning means for tuning said receiver over a range of frequencies, resonance adjusting means for automatically bringing said receiver into substantially exact resonance with a first high-frequency signal selected by approximate setting of said tuning means but for releasing said first signal when said tuning means is adjusted to select a second signal, means but for preventing response from said receiver whenever the amplitude of the signal impressed across said means is less than a certain value and until said amplitude exceeds a substantially higher value, and means independent of said response-preventing means for accelerating the release of said first signal by said resonance adjusting means.

18. A radio receiver including in combination, tuning means, resonance adjusting means for automatically bringing said receiver into substantially exact resonance with a first high-frequency signal selected by approximate setting of said tuning means but for releasing said first signal when said tuning means is adjusted to select a second signal, means for automatically regulating the high-frequency amplification of said receiver inversely in accordance with the

strength of said first signal, means for preventing response from said receiver whenever the amplitude of the signal impressed across said means is less than a certain value and until said 5 amplitude exceeds a substantially higher value, and means independent of said response-preventing means for accelerating the release of said first signal by said resonance producing means.

19. The method of preventing undesired sound 10 reproduction in a radio receiving system tunable to selectively receive any one of a number of different carriers throughout a wide range of frequencies and providing resonance adjustment for automatically bringing said system into substantially exact resonance with a first carrier selected by approximate tuning thereof but releasing said first carrier when said system is 15 tuned to receive a second carrier, which comprises maintaining said system in a substantially inoperative condition whenever the amplitude of said first carrier is less than a certain minimum value and until said amplitude exceeds a value 20 substantially higher than said minimum value, rendering said system operative as soon as said 25 amplitude exceeds said higher value, and independently accelerating the release of said first carrier.

20. The method of preventing undesired sound reproduction in a radio receiving system tunable to selectively receive any one of a number of different carriers throughout a wide range of frequencies and providing resonance adjustment for automatically bringing said system into substantially exact resonance with a first carrier selected by approximate tuning thereof but releasing said first carrier when said system is 10 tuned to receive a second carrier and also providing automatic regulation of the high-frequency amplification of said system inversely in accordance with the amplitude of said first carrier, which comprises maintaining said system in substantially inoperative condition whenever the 15 amplitude of said first carrier as modified by said automatic high-frequency amplification regulation is less than a certain minimum value and until said modified amplitude exceeds a value substantially higher than said minimum value, 20 rendering said system operative as soon as said modified amplitude exceeds said higher value, and independently accelerating the release of said first carrier.
